(57) **CLAIM**

We claim the ornamental design for a screened bait keeper with hinged lid for removable insertion into live well of boat, as shown and described.

DESCRIPTION

FIG. 1 is a perspective view of a screened bait keeper with hinged lid for removable insertion into live well of boat showing our new design;

FIG. 2 is a front elevational view thereof;

FIG. 3 is a rear elevational view thereof;

FIG. 4 is a right side elevational view thereof, the left side elevational view being a mirror image thereof; and,
FIG. 5 is a top plan view thereof, the bottom plan view being identical thereto.
